UNITED STATES PATENT OFFICE.

LIONEL ALFRED WHARRAD, OF REDDITCH, ENGLAND, ASSIGNOR TO WHARRAD ENGINEERING COMPANY LIMITED, OF REDDITCH, ENGLAND, A CORPORATION.

MACHINE FOR HEATING AND TEMPERING NEEDLES.

1,177,218.

Specification of Letters Patent. Patented Mar. 28, 1916.

Application filed January 26, 1914. Serial No. 814,489.

To all whom it may concern:

Be it known that I, LIONEL ALFRED WHARRAD, a subject of the Kingdom of Great Britain, residing at Wharrad Works, Redditch, in the county of Worcester, England, have invented certain Improvements in Machines for Heating and Tempering Needles, of which the following is a specification.

This invention comprises a machine for use in connection with the tempering or heating of needles, fish hooks, pens, screws, and other articles of a like nature.

It has before been proposed to heat needles and similar articles within an inclined rotary tube, to one end of which the needles are introduced, and from the other end of which the needles egress, provision being incorporated for adjusting the inclination of the tube.

According to the present invention the needles or other articles are heated within a rotating chamber of cylindrical or other suitable shape, the wall of which chamber is internally heated.

In the present invention the goods advantageously egress from the end of the chamber by which they have been introduced, the chamber being advantageously installed according to a cantaliver arrangement by virtue of which it can be elevated, while the needles or other articles are undergoing the process, after which the chamber can be caused to oscillate into a position in which the needles or other articles readily egress by gravitation. The means for imparting rotary movement to the chamber are transmitted through the medium of a shaft which is concentric with the axis of oscillation of the chamber, whereby the

driving mechanism is unaffected by the oscillatory movement of the chamber. The space for containing the needles or other articles is advantageously of annular formation, and the chamber is advantageously closed at one end by a hollow end wall containing the heating medium, and which end wall communicates with the outer heating wall, the heating medium or fuel therefor being supplied by way of a tube or conduit upon which the chamber is mounted and through the medium of which tube or con-

duit the chamber may be oscillatorily mounted upon the frame or stand of the machine.

In order that this invention may be clearly understood and readily carried into practice, reference may be had to the appended explanatory sheet of drawings, upon which;

Figure 1 is an elevation of a machine according to the present invention. Fig. 2 is a central section of the chamber part of the machine shown in Fig. 1. Fig. 3 is a part central sectional elevation of the machine shown in Fig. 1.

In a convenient embodiment of the present invention, the cylindrical chamber *a* is constructed of sheet metal, there being an inner and outer wall of sheet metal in order to form a hollow wall for the chamber. This hollow wall is continued to permanently close one end of the chamber, and a concentric hollow cylinder *a*¹ is provided within the interior of the chamber *a* and extending for substantially the whole length of same, the hollow walls and central cylinder being throughout constructed of the sheet metal which is lined internally with asbestos as shown at *a*⁴. At its closed end the chamber is mounted upon a tubular member *b* by which it is carried the said tubular member *b* being rotatably mounted in a bracket *c* in such a manner that the chamber projects or overhangs, while at the other end of the chamber a removable closure or door *a*² is provided for completely inclosing the annular space between the central cylinder and the hollow wall of the chamber in which the articles to be treated are placed. Said door may if desired be furnished with a mica window to facilitate inspection of the goods while contained within the chamber. A gas burner *d* is provided with an elongated nozzle *d*¹ adapted to project into the end of the tubular member remote from that at which the latter is secured to the chamber in such a manner that an annular space is left between the gas nozzle and the tubular member to admit air and permit of a Bunsen flame within the hollow walls of the chamber. The said burner may consume ordinary or other gas or liquid fuel. The nozzle *d*¹ is adjustable longitudinally in relation to the tubular member *b* and it may be fur-

nished with a conical part which according to the position of longitudinal adjustment more or less closes or opens the ingress extremity of the tubular member *b*. The adjustment may be effected by loosening and tightening the wing nut *h* provided upon a screwed stem which passes through an elongated hole in the bracket which carries the nozzle *d*¹. A small rotary or other blower 5 may if desired be incorporated to create a forced draft insuring the proper application of the flame to the heating part of the machine. At the juncture of the tubular member with the chamber a wire gauze dia- 10 phragm *e* is provided to prevent the flame from firing back to the nozzle *d*¹. By this arrangement a flame is obtained throughout the walls of the chamber, there being suitable vents or outlets *a*³ provided for the 15 products of combustion at the extremities of the wall remote from the point at which the combustible enters.

The bracket *c* which carries the tubular part *b* to which the chamber *a* is secured 20 embraces the said part at two points in its length in order to effectively support the chamber and the said bracket is furnished with a transverse pivot *f* by which the axis of the chamber can be inclined or tipped, the 25 said pivot working in a suitable stationary frame or support *g*. Concentrically disposed in relation to this pivot and advantageously passing through same is a driving shaft *f*¹ having a worm *f*² adapted to gear 30 with a worm wheel *f*³ provided upon the tubular member so that power may be imparted to rotate the latter. As the driving shaft is concentric with the pivot upon which the chamber may be displaced, the tilting or 35 tipping of the chamber can be effected without interfering with the driving connection between the driving shaft and the worm wheel.

To provide for the adjustment of inclination of the chamber and locking of same at 40 any particular inclination, the pivot which moves with the chamber is furnished with an arm *h* with which a screwed stem *i* co-operates, the said screwed stem working within 45 a threaded boss *i*¹ on the stationary frame of the machine so that by rotating the screwed stem by a hand lever *i*² provided thereon, movement is imparted to the arm. The arm may be entirely separate or disengaged from 50 the screwed stem but may remain in contact therewith by the weight of the barrel in which case the screwed stem forms a stop by 55 which the barrel is retained in the projected position. The screwed stem may however 60 be coupled to the arm by a link or the like in such a manner that the barrel is positively locked by the screw from movement in either direction at any adjustment at which it is placed.

65 It will be understood that change in form

and proportion of parts of the preferred embodiment of my invention as set out herein may be made without departing from the spirit and scope of my invention as set forth in the appended claims.

70 What I claim as my invention and desire to secure by Letters Patent is:—

1. The combination in a machine for heating and tempering needles, fish hooks, pens, screws and the like, of a receptacle of an 75 angular formation having a hollow end wall and hollow side walls communicating with said hollow end wall, means for supplying heat to the interior of said hollow walls, a hollow tube carrying said receptacle and adapted to convey the heat thereto, means for supporting said tube and receptacle, and means for varying the angular position of the axis of the said tube and receptacle with respect to the horizontal. 80

85 2. The combination in a machine for heating and tempering needles, fish hooks, pens, screws and the like, of a receptacle closed at one end and having hollow walls, a 90 closure for the other end of said receptacle, a concentric hollow cylinder within said receptacle and communicating with the said hollow walls, means for internally heating said walls and cylinder, means for varying the inclination of the axis of said receptacle in a tilting movement, means for rotating said receptacle, and an asbestos lining 95 for said hollow walls and cylinder.

100 3. The combination in a machine for heating and tempering needles, fish hooks, pens, screws and the like, of a receptacle having spaced inner and outer walls inclosing the sides and bottom of a chamber open at one end, a hollow spindle connected with the bottom of said receptacle whereby the 105 receptacle is supported, means for introducing hot gases through said spindle into the space between said walls, means for rotating said spindle and means for tilting said spindle. 110

115 4. The combination in a machine for heating and tempering needles, fish hooks, pens, screws and the like, of a receptacle having spaced inner and outer walls inclosing the sides and bottom of the chamber open at one end, a hollow spindle connected with the bottom of said receptacle whereby the receptacle is supported, means for introducing hot gases through said spindle into the space between said walls, means for rotating said spindle, means for tilting said spindle, the said bottom wall being disposed inwardly so as to form a recess opposite the end of said spindle. 120

125 5. The combination in a machine for heating and tempering needles, fish hooks, pens, screws and the like, of a receptacle having spaced inner and outer walls inclosing the sides and bottom of the chamber open at one end, a hollow spindle connected with 130

- the bottom of said receptacle whereby the receptacle is supported, means for introducing hot gases through said spindle into the space between said walls, means for rotating said spindle, means for tilting said spindle, the said bottom wall being disposed inwardly so as to form a recess opposite the end of said spindle, and a cover for said chamber.
- 10 6. The combination in a machine for heating and tempering needles, fish hooks, pens, screws and the like, of a stationary frame, a pivot carried by said frame, a bracket carried by said pivot, a hollow axle carried by said bracket, a receptacle having inner and outer walls spaced apart and inclosing the sides and bottom of a chamber
- 15 open at one end, the aperture in said hollow spindle being arranged in connection with the space in the bottom of said receptacle, 20 means for introducing hot gases through said spindle into the space between said walls, an arm fixed to said pivot, a screw for adjusting the position of said arm so as to tilt the receptacle, a shaft passing 25 through said pivot, a worm on said shaft, and a gear on said axle whereby the receptacle may be turned.
- In witness whereof I have hereunto set my hand in the presence of two witnesses. 30
- LIONEL ALFRED WHARRAD.
